Smut Mill

Patented Aug 23, 1831.

Henry Ward & Stephen Fellows, of Sandwich, New Hampshire.

Wards Patent.

The schedule referred to in their Letters, Patent and making part of the same containing a description in the words of the said Henry Ward & Stephen Fellows themselves of their improvement in the common smut mill or machine called the Improved portable Smut-machine.

To all to whom these presents shall come,
Be it known that we Henry Ward & Stephen Fellows both of Sandwich in the County of Stafford and State of New Hampshire, have invented a new and useful improvement in the common Smut-machine or machine called the Improved Portable Smut-machine, for the purpose of cleaning grain before grinding, and that the following is a full and exact description of the construction and operation of the said Machine as invented or improved by us.
First; We form a box or chest of suitable boards or planks, with nails, pegs, or dovetails in the common way; It is four feet in length, one and one half feet in width, with a depth of two feet nine inches, though these proportions may vary and be a little more or somewhat less, to accommodate the wish of the constructor, or to suit the exigencies of the case. The box or chest is supported upon pedestals, feet, or legs, about one foot long; Upon one side is a movable door for the convenience of cleaning out the dust and chaff. The top may be covered when desired.

2^d; We then fasten with nails or otherwise upon the bottom and near the centre of said chest two blocks of wood about eight inches high and ten inches apart, we fasten upon the top of these blocks a board some larger than the diameter of the curve and cover the top of this board with sheet iron or some other suitable metallic substance we have a round opening in the centre of the above named board and iron about three inches in diameter, to receive the spindle of a cylinder, and to admit air into the curve, around this opening is raised a ridge or eminence to prevent the grain from passing.

3^d; We then make a circular curve of sheet iron or other suitable metal

substance about fourteen inches high, and twelve inches in diameter, punched full of holes either square oblong or round from the circumference towards the center, so as to form sharp points or canines upon the inside thereof, the ends of which curve may be of a zig, or the lower end may be the larger. This curve is made to beat down upon the cover of the block, aforesaid to preserve the ends round and keep them steady by means of a plank cut circular to conform thereto, and extend to the sides of the chest. A cap cover is made to said cover in two pieces, with a hole through the center sufficiently large for the spindle of a cylinder & to receive the grain from a sieve, and an opening is also made in one edge of the cover at a bottom for the grain to pass out.

4. We then form a cylinder of solid wood or otherwise to be plated on the end conform to the curve as herinafter described the lower end of which cylinder is formed hollow with a rim on the edge for the purpose of shutting down around the ridge or canines above described. The circumference of this cylinder, we then cover with tin, sheet iron, or other suitable metallic, smooth or made rough like a grater, or in some cases it may be without said covering, the cylinder is armed or roughed with metallic heads, metallic stamps or other hard canines, about two inches long and one inch wide at one end and about one half inch wide, at the other somewhat resembling the letter V, We then mark straight parallel lines around the cylinder an inch apart, commencing within one inch from the bottom, and insert the said metallic heads, stamps or canines into the same either at right angles thereto or slanting upon said marked lines thus, (1) for the purpose of longer retaining the grain in the curve, so that said heads &c. when placed would form diagonal lines, and project out upon the cylinder, three fourths of an inch. Or that part of the said heads, stamps, or canines, which project from the cylinder and which strike the grain, may be made rough somewhat like a rasp, several such driven in a cluster may answer as a substitute for the heads, stamp or canines. Or in another way we cover the cylinder with sheet iron or a suitable metallic substance cut into oblong strips about one inch wide, or three and one half inches long with the ends square or diagonal as we

shape. about three quarters of an inch of one end, is bent outwards on a line parallel with the other end, forming an eminence and resembles the letter T. The longest end is then confined upon the cylinder, so that when placed there are which are bent outwards, range the same as the stumps or eminences before described and may be caught by pinching if necessary.

5. We then make an iron shaft or spindle about two feet six inches long and one inch in diameter, which passes through the centre of said cylinder, and extends out through the bottom about eight inches resting on a metallic step or box placed in a bridge-tree near the bottom of said chest, which bridge-tree passes through one side of the chest and is used for the purpose of regulating the cylinder, the upper part of the shaft or spindle, is used to & cool in a block of wood called a "plummer block" extending across the chest near the top. Upon that part of the spindle which extends above the plummer block, we affix a whorl or drum for the purpose of carrying said grain with a bar or belt, which whorl, or drum, is four inches in diameter, one and one half inches thick, or of such a size as the speed requires. Upon said spindle we affix one whorl, about two inches in diameter and one inch thick, and another immediately below and adjoining thereto, four inches in diameter, and one inch thick, both of which last mentioned whorls are between the said plummer blocks and cylinder close to the block.

This shaft together with the cylinder when completed must be placed perpendicular in the centre of the curve leaving about one third of an inch's space between the eminences of the cylinder and those of the curve.

6. We have two small sines, one over the other fastened together and hung in such a manner that the upper or coarse one descends from the curve with the lower end open, the other descends toward the curve, the upper one receiving the grain from a hopper of common form, and retains the birds which pass off into the chest, and permits the grain to fall upon the wood. The foul seeds pass through the second sine into the chest and the grain is conducted through the cap or covering of the curve.

The end of the sine frame remotest from the curve is hung with a strap or line fixed to a roller for the purpose of regulating the feed, the other end rest upon the cap or cover of the curve. These being now shaken by a hand also

6780

attached to a small crank near the end of the chest opposite to the side the arm of which crank is about one third of an inch long. Around the end of this crank is a whurr four inches in diameter which occurs and is covered by a band from a whurr on the said cylinder shaft six inches in diameter.

7th we form a spout about three feet long which stands somewhat obliquely with the lower end placed so as to receive the wind from a fan with the upper part shortest, to let the grain fall through the bottom of the chest or it may be conducted out at the side. The spout then passes up by the lower part of the curve, with a hole in one side opposite the opening in the curve for the purpose of receiving the grain, it then continues about two feet through which the chaff is blown into the chest.

8th we also make a curve for a fan about eight inches in diameter and four inches deep and place it perpendicular upon the bottom of the chest at the end opposite the sieve, near the corner, through the bottom of the chest, in the centre of this curve is made a circular hole six inches in diameter to admit air into the curve. In this curve upon the edge near the top is made an opening corresponding with the spout. Also we have a fan as large as will operate in this curve made of wood or chest iron attached to a wooden or iron shaft, which stands parallel with the spindle of the cylinder, and has a whurr near the upper end about four inches in diameter, and one inch thick to receive a bolt passing around a whurr on the spindle of the cylinder of the same size.

This shaft or spindle, rests upon a bridge tree afford to the bottom of the chest and receives therein and at the top it is fastened firmly to that of the cylinder. The curve of the fan, is covered with a board in two pieces. What we consider new in said machine for which we ask an exclusive privilege is, Firstly placing the seeds in a chest, Secondly the shape of the boards, 3rd Thirdly in making the rough, Fourthly the manner of placing them in the cylinder, Fifthly the driving of the rods in clusters, Sixthly the cutting of the chest in 6th into strips and making them rough like a sack or goat.

Advantages. what we consider as advantages which this machine

6720X

invention the common dust machine, are the following.

Firstly - The saving of expense - Secondly, it takes less power to operate the same - Thirdly, in having the dust retained in the chest, fourthly, it is smaller and more portable. Fifthly, it may be put in operation with a belt by almost any other machinery with very little expense.
